CLAIM

The ornamental design for a suction cup attachment for magnetic mounting system, as shown and described.

DESCRIPTION

FIG. 1 is a front perspective view showing the suction cup attachment for magnetic mounting system of the present invention;

FIG. 2 is a top view thereof;

FIG. 3 is a left side view thereof;

FIG. 4 is a front view thereof;

FIG. 5 is a rear view thereof;

FIG. 6 is a right side view thereof; and,

FIG. 7 is bottom view thereof.

In the drawings, the broken line showings are for the purpose of illustrating portions of the suction cup attachment for a magnetic mounting system or environmental structure and forms no part of the claimed design.
